UNITED STATES PATENT OFFICE.

EDGARD DUPONT, OF ANTWERP, BELGIUM.

GRATE STRUCTURE FOR BOILERS.

Application filed May 12, 1924. Serial No. 712,676.

To all whom it may concern:

Be it known that I, EDGARD DUPONT, a subject of the King of the Belgians, residing at Antwerp, Belgium, 56 Rue Robert 5 Mols, have invented new and useful Improvements in Grate Structures for Boilers, of which the following is a specification.

The present invention relates to an improved grate-structure with fire bridge, 10 made entirely of cast iron and applicable to the furnaces of steam boilers employing solid fuel, and more particularly to marine boilers.

The structure according to the invention 15 substantially comprises a horizontal grate composed of a plurality of removable and interchangeable grate-bars, of cuneiform cross section and of sinuous or waved conformation in the longitudinal direction, resting at their ends on suitable grate-bar bearers, in combination with a fire bridge comprising a plurality of removable and interchangeable grate-bars curved to form a quarter of a circle, of suitable cross section 20 and having cut away portions forming corrugations along a portion of the length of their sides, which grate-bars are arranged side to side and bear at their lower and upper ends respectively on a dead plate which 25 also forms a grate-bar bearer for one end of the horizontal grate, and on the upper edge of a supporting plate arranged substantially at right angles to the said dead plate, the said 30 grate-bars of the fire bridge having recesses 35 formed in the edges of their upper portion so as to constitute by their juxtaposition apertures for the passage of cooling air. The invention further comprises the provision of means to lock the fire bridge grate- 40 bars in position or disengage them at will, by means of a flat locking bar passing through a slot in the supporting plate for the upper ends of the said grate-bars, and capable of being operated through the me- 45 dium of suitable rod connections.

In order that the invention may be more readily understood, an embodiment thereof is, by way of example only, described in detail hereunder by reference to the accompanying diagrammatic drawings, in which:

Figure 1 is a longitudinal section through a grate-structure in accordance with the invention,

Figure 2 is a corresponding plan, a portion of the grate-bars being removed, and 55

Figures 3, 4 and 5 show the transverse section of a grate-bar, taken respectively on the line III—III, IV—IV and V—V of Figure 1.

Referring to the said drawings, the structure according to the invention comprises a grate-bar bearer 1 adapted to receive the ends 2 of the grate-bars constituting the horizontal grate adjacent the furnace front. The horizontal grate is flat and forms a 60 single panel comprising a certain number of separate removable grate-bars 3 having a sinuous or waved shape in the direction of their length, as illustrated by Figure 2. These bars 3 are arranged loosely side to 65 side, with the necessary clearance between their ends 2 and 2' and between their central lugs 4, to allow free dilatation or expansion in all directions. These bars 3 have a 70 cuneiform cross section so that the whole 75 forms a grate-plate for a furnace with forced draught by suction of air.

The described arrangement allows the cleaning of the furnace to be effected easily 80 by the introduction of a poker-iron with pivoted hook in the spaces 5 between the bars 3 in order to break and destroy the cakes, masses of slag and other residues of combustion. Moreover the particular sinuous or waved conformation of the grate- 85 bars enables the effective surface of the grate to be appreciably increased by increasing the length of the spaces 5 between the bars while maintaining the width of such spaces, so that the draught will be intensified, whereby an increase of the rate of 90 vaporization will be obtained.

The rear ends 2' of the grate-bars 3 rest on a grate-bar bearer 6 which is integral with a dead plate 7 forming a portion of a 95 casting 8 which is of such a cross section as to provide also a support 9 for the lower ends 11 of the fire bridge grate-bars 10. The fire bridge comprises a quarter circle 100 grate composed of a certain number of curved removable grate-bars 10 arranged loosely side to side and having cut away portions forming corrugations along a portion of the length of their sides, as illustrated by Figure 2. These fire bridge bars 105 10 are supported at their upper ends 11' on

a supporting plate 12 arranged substantially at right angles in relation to the dead plate 7 and extending along the whole length of the fire bridge, and the said bars 10 are maintained in position through the engagement of a lug 13 provided under their upper ends 11' in a corresponding longitudinal groove 14 provided in the upper edge of the supporting plate 12.

10 The dead plate 7 possesses two openings 15 for the admission of air under the grate-bars of the fire bridge this air, arriving from the ashpit, passing through the fire bridge grate under the influence of the draught.

Seen in cross section, the upper portion of the grate bars 10 has a shape recalling that of the head of a wood screw or of a nail as illustrated by Figures 4 and 5 respectively, so as to set up a suction of air to bring the latter into contact with the unburnt gases in the combustion chamber, in order to ensure the ignition thereof and thus to increase further the efficiency of the generator. Close to their upper ends 11', the grate-bars 10 moreover have a series of recesses formed in their edges so as to constitute by their juxtaposition small circular apertures 16 for the passage of cooling air.

30 The means provided to lock the grate-bars 10 in position comprise a locking bar 17 of flat section, passing through a longitudinal slot 18 cut in the supporting plate 12. This flat locking bar 17 is secured to the upper ends of a pair of rods 19 fixed on a horizontal bar 20 capable of pivoting in small bearings 21 provided on the supporting plate 12. At their lower ends the said rods 19 are pivotally connected to an operating rod 22 extending under the furnace towards the furnace front, from where it may be operated by means of an operating handle 23 with which it is provided. The flat locking bar 17 is capable of engaging in suitable notches or recesses 24 cut into the ends 11' of the bars 10, so that by operating the rod 22 the said grate-bars may be locked in the position required for a good efficiency by engaging the locking bar 17 in the recesses 24, or may be rendered free by disengaging the said locking bar 17 from the said recesses 24. The grate-bars 10 being thus rendered free, the removal and the renewal of single grate-bars may be readily effected, and an intermediate grate-bar may be added without it being necessary to remove the adjacent bars.

The lower end of the fire bridge grate-bars 10 has a recess 25 cut therein for engagement with a fillet 26 of the portion 9 of the dead plate supporting the said ends, whereby the said grate bars are maintained more securely in the proper position.

60 It is to be observed that the shape of the cross section of the bars of the two grates

results in producing an intensified draught due to the compression of the air resulting from the gradually narrower section of the air passages between the lateral inclined faces of the adjacent grate-bars. 70

I claim:

1. In a grate-structure for steam boilers, the combination of: a horizontal grate-plate comprising grate-bar bearers and a plurality of removable and interchangeable longitudinally waved grate-bars of cuneiform cross section arranged side to side and resting at their ends on the said grate-bar bearers; a quarter-circular fire bridge grate comprising a plurality of removable and interchangeable curved grate-bars arranged side to side and having cut away portions forming corrugations along a portion of the length of their sides and a series of recesses formed in their edges close to their upper ends in such manner as to constitute by their juxtaposition apertures for the passage of cooling air; a horizontal dead plate arranged under said fire bridge grate and cast with a portion adapted to form a support for the lower ends of the fire bridge grate-bars; a supporting plate arranged substantially at right angles to the said dead plate and extending under the upper ends of said grate-bars; and hand controlled means for locking the last-named grate-bars in position; substantially as described. 90

2. In a grate-structure for steam boilers, the combination of: a horizontal grate-plate comprising grate-bar bearers and a plurality of removable and interchangeable longitudinally waved grate-bars of cuneiform cross section arranged side to side and resting at their ends on the said grate-bar bearers; a quarter-circular fire bridge grate comprising a plurality of removable and interchangeable curved grate-bars arranged side to side and having cut away portions forming corrugations along a portion of the length of their sides and a series of recesses formed in their edges close to their upper ends in such manner as to constitute by their juxtaposition apertures for the passage of cooling air, said grate-bars having a cross section of a width increasing gradually in an upward direction for the greater part of their height and in notably accentuated proportions at the top; a supporting plate arranged substantially at right angles to the said dead plate and extending under the upper ends of said grate-bars; and hand controlled means for locking the last-named grate-bars in position; substantially as described. 110

3. In a grate-structure for steam boilers, the combination of: a horizontal grate-plate comprising grate-bar bearers and a plurality of removable and interchangeable longitudinally waved grate-bars of cuneiform cross section arranged side to side and rest- 125

ing at their ends on the said grate-bar bearers; a quarter-circular fire bridge grate comprising a plurality of removable and interchangeable curved grate-bars arranged side to side and having cut away portions forming corrugations along a portion of the length of their sides and a series of recesses formed in their edges close to their upper ends in such manner as to constitute by their juxtaposition apertures for the passage of cooling air, said grate bars having a recess cut in the web-portion thereof at their upper ends; a horizontal dead plate arranged under said fire bridge grate and cast with a portion shaped to support the lower ends of the last-named grate-bars and including a fillet adapted to engage in the recesses cut in the said lower ends; a supporting plate arranged substantially at right angles to the said dead plate and extending under the upper ends of said grate-bars; and hand controlled means for locking the last-named grate-bars in position; substantially as described.

4. In a grate-structure for steam boilers, the combination of: a horizontal grate-plate comprising grate-bar bearers and a plurality of removable and interchangeable longitudinally waved grate-bars of cuneiform cross section arranged side to side and resting at their ends on the said grate-bar bearers; a quarter-circular fire bridge grate comprising a plurality of removable and interchangeable curved grate-bars arranged side to side and having cut away portions forming corrugations along a portion of the length of their sides and a series of recesses formed in their edges close to their upper ends in such manner as to constitute by their juxtaposition apertures for the passage of cooling air, said grate bars having a recess cut in the web-portion thereof at their upper ends; a horizontal dead plate arranged under said fire bridge grate and cast with a portion adapted to form a support for the lower ends of the fire bridge grate-bars; a supporting plate arranged under the upper ends of the said grate-bars substantially at right-angles to the said dead plate and having a longitudinal slot cut therein close to its upper edge; and means for locking the last-named grate-bars in position, comprising a flat locking bar passing through said slot and a set of suitably arranged rod-connections for operating said locking bar from the furnace front for engagement in or disengagement from the aforesaid recesses of the upper ends of the said last-named grate-bars; substantially as described.

In testimony whereof I signed hereunto my name in the presence of two subscribing witnesses.

EDGARD DUPONT.
